MACHINE FOR PRESSING GARMENTS.

1,291,222.

Specification of Letters Patent.

Patented Jan. 14, 1919.

Application filed July 3, 1917. Serial No. 178,421.

To all whom it may concern:

Be it known that I, JAMES B. SPENCER, a citizen of the United States of America, and resident of Syracuse, in the county of Onondaga, in the State of New York, have invented new and useful Improvements in Machines for Pressing Garments, of which the following, taken in connection with the drawings, is a full, clear, and exact description.

This invention relates to certain improvements in machines for pressing garments, such as coats, vests, trousers, skirts and the like by the simultaneous application of moisture, pressure and heat for softening the fabric to give it the necessary pliability, shaping and fixing the shape of the garment to the desired form and sterilizing and drying the garment, all in one and the same operation, so that immediately following the separation of the pressing elements preparatory to removing the garment, the steam used for supplying the moisture readily evaporates from the surface of said garment and not only restores the nap, but also accelerates the drying so that the garment may be put on and worn with perfect safety directly from the pressing operation.

In machines of this character, the upper pressing element or press head is movable toward and from a substantially horizontal lower pressing element, commonly termed the buck, about an axis parallel with and some distance to the rear of said buck, and is usually forced to its pressing position by means of a pedal lever and suitable connections between the pedal lever and rock arm upon which the head is mounted against the action of a counterweight or retracting spring, suitable provision being made for temporarily locking the head in its pressing position.

It has been found, however, that in pressing certain parts of garments, such as the lapels, pocket flaps, sleeve cuffs, trouser cuffs, and the like, considerably greater pressure is required than for the body of the garment in order to meet the demand that those parts shall lie substantially as flat and smooth as the main body and that the folds of the collars and cuffs of such garments shall maintain their shape for a longer period of time.

The pressure produced by the usual foot pedal connected in the manner described,

while sufficient for the main bodies of the garments, is not sufficient to meet the demands for pressing the special parts of the garment referred to, and the main object of my present invention is to provide such a machine with simple means for bringing the pressing elements together with an increased force beyond that produced by the mechanically-operated means or foot lever, and at the same time permitting the machine to be used in the ordinary way for pressing the bodies of the garments.

Other objects and uses relating to specific parts of the machine will be brought out in the following description.

In the drawings—

Figure 1 is a side elevation of a garment pressing machine embodying the various features of my invention.

Fig. 2 is a transverse vertical sectional view taken on line 2—2, Fig. 1.

As illustrated, this machine comprises a supporting base or frame —1— having a horizontal ledge —2— and a bracket —3—, the latter extending upwardly from the rear portion of the frame for receiving and supporting a rock arm —4—.

A pair of upright cylinders —5— are mounted upon the front portion of the horizontal ledge —2— of the frame —1— and are provided with laterally projecting flanges 6 for supporting a table, as —7—, a portion of which is shown by dotted lines in Fig. 2.

Movable in the upper ends of these cylinders are pistons —8— closed at the top and carrying at their upper ends a horizontal buck or lower pressing element —9— which is secured to the upper ends of the pistons —8— by clamping bolts —10— so as to cause the buck to move vertically with the pistons.

The outer sides of the upper ends of the cylinders and pistons are provided with laterally projecting lugs —11— and —12— having vertically registering apertures for receiving a pair of studs —13— which are preferably screwed into the lugs —12— and extend some distance below the lower faces of the lugs —11—, the lower ends thereof being threaded and provided with nuts —14— constituting adjustable stops coacting with the lugs —11— for limiting the upward movement of the pistons —8— and buck —9— supported thereby.

The rock arm —4— is fulcrumed inter-

mediate its ends at —15— upon the upper end of the bracket —3— so as to swing about an axis some distance at the rear of and parallel with the buck —9— and carries at 5 its front end a press head or upper pressing element —16— directly over said buck so as to swing into and out of pressing action therewith.

Any suitable mechanical means may be 10 employed for rocking the arm —4— to force the press head to its pressing position and for locking those parts in such position, that shown being similar to the corresponding construction as set forth in my Patent No. 15 1,164,616, dated December 14, 1915,—in that it consists of a forwardly and rearwardly extending pedal lever —17— of the first kind fulcrumed at —18— on the main supporting frame —1— and having its rear end 20 connected by a toggle —19— to an adjusting screw —4'— on the rearwardly extending end of the rock arm —4.

The front portion of the pedal lever —17— just back of the pedal is connected 25 by a link —20— to one arm of a bell-crank lever —21— which is pivoted at —22— to a bracket —23— on the main supporting frame and has its other arm connected by a link —24— to one end of a second toggle 30 —25—, the other end of the toggle —25— being also connected to the adjusting screw —4'— at the same point, as —26—, at which the toggle arm —19— is connected.

The flexing joint of the toggle —25— lies 35 back of the similar flexing joint of the toggle —19— and forms a limiting stop for the latter when the press head is forced to its pressing position.

The lower arm of the toggle —25— extends across the corresponding arm of the 40 toggle —19— and is pivoted thereto at —27— so that when the pedal end of the lever —17— is depressed against the action of a retracting spring —28—, the flexing 45 joints of the toggle levers —19— and —25— will be forced to the position indicated in Fig. 1, and the press head will be positively forced to its pressing position, and when elevated by the retracting spring the flexing 50 joints of the toggles —19— and —25— will be moved away from each other and the press head will be positively raised to its normal open position.

The toggles —19— and —25— are adjust- 55 ed so that in raising and lowering the press head, the flexing joint of the toggle —19— will be moved to opposite sides of a direct line between the points of connection of said toggle with the pedal lever —17— and ad- 60 justing screw —4'— on the rear end of the rock arm —4.

That is, when the pedal end of the lever —17— is depressed to force the press head 65 downwardly to its pressing position, the flexing joint of the toggle —19— will be

moved to the left of the direct line —a— and will be limited in such movement by the engagement of the flexing joint of the toggle —25—, thereby locking the press head in its pressing position under a certain maximum 70 degree of pressure of which the lever —17— and its connections with the rock arm —4— are capable of producing.

A pedal release lever —29— is pivotally mounted upon the lower front portion of the 75 main frame —1— with its rear end directly under the pedal lever so that when the front end of the release lever is depressed by the foot, its rear end will engage and raise the front end of the pedal lever, thereby causing 80 the link —20— to rock the front end of the bell-crank lever —21— upwardly and its opposite end forwardly to exert a forwardly drawing force upon the pivotal connection 85 —27— between the lower arms of the toggles —19— and —25—, thereby moving the flexing joint of the toggle —19— forwardly to the right of the direct line to break the lock and allow the press head and pedal lever to be returned to their normal raised 90 positions by the spring —28—.

It is evident, however, that any other means for raising and lowering the press head and for locking it in its pressing position may be employed without departing 95 from the spirit of my invention, which lies more particularly in the combination of any means for raising, lowering and locking the head with the fluid-pressure operated means, as the pistons —8—, for forcing the buck 100 —9— into further pressing engagement with the locked head —16— under a greater pressure than that which is capable of being produced by the operation of the pedal lever —17— and its connections with said head. 105

As illustrated, the buck —9— and press head —16— are provided with steam-heating chambers —30— and —31— to which steam is supplied from any available source through branch pipes —32— and —33—, the 110 water of condensation being drawn off from said chambers through branch pipes —34— and —35—.

The purpose of supplying steam to these 115 chambers is to keep the pressing elements in a heated condition while the machine is in operation, and also to aid in expediting the drying of the garments to which moisture has been applied from an external source, usually the same as that which supplies steam to said chambers. 120

This moisture is supplied to the garments under pressure by steam, and for this purpose I have provided the press head —16— with a steam-distributing chamber —36— 125 directly under the heating chamber —31— and substantially coextensive with the area of the pressing surface of the head.

The chamber —36— communicates with the source of supply through the chamber 130

—31— and ports —37—, which latter are controlled by a normally closed valve —38— adapted to be opened at will for an instant by means of a hand lever —38'— to admit a blast of steam to the chamber —36—.

From this chamber steam is admitted to the garment through a perforated press plate —39— forming the bottom of the chamber —36— and press head —16—.

10 The lower face of the perforated plate —39— may be covered by a steam-pervious pad —40—, shown by dotted lines in Fig. 1, to distribute the steam more evenly over and upon the garment under pressure.

15 The buck —9— is provided with a suction chamber —41— overlying the heating chamber —30— and covered by a perforated plate —42—, said chamber —41— and plate —42— being substantially coextensive with 20 the pressing area of the buck and corresponds in form and area to that of the press head.

The suction chamber —41— is connected to a suction pipe —43— which, in turn, is 25 connected to a suction device —44— similar to that set forth in my pending application, Serial No. 34,130, filed July 15, 1915,—in that it consists of a steam ejector to which steam is supplied through a pipe —45— 30 connected to the same source of supply as the pipe —32— leading to the heating chamber —30— and provided with a self-closing valve —46— adapted to be opened at will 35 by a pedal lever —47— through the medium of a valve rod —48— connected thereto.

The suction device —44— is provided with a discharge pipe —49— leading to a waste pipe —50— or other place of delivery 40 outside of the building if desired.

The function of this suction device is to withdraw steam and moisture from the garment while under pressure so as to prevent the escape of such steam into the room in which the machine is located, and also to accelerate the drying and cooling of the garment, which, in turn, materially aids in setting the shape of the garment to the form in which it is pressed.

50 The pistons —8— are preferably operated by steam pressure from the same source of supply as that which furnishes the steam to the heating chambers of the pressing elements, and for this purpose the lower ends 55 of the cylinders are connected by branch pipes —51— to a valve —52— to which is connected a steam supply pipe —53— and an exhaust pipe —54—, the pipe —53— being connected to the same source of supply as the pipe —32—, while the exhaust pipe —54— may be connected to the drainage pipe —50—, or to any other place of delivery of the exhaust steam or water of condensation.

65 The valve —52— is provided with an

operating handle —55— and is constructed so that in one position it will open communication between the steam supply pipe —53— and interior of the cylinders —5—, at which time the communication with the 70 exhaust pipe —54— will be closed, or it may be shifted to another position to open the cylinders to the exhaust and to close the steam inlet to allow the pistons with the buck thereon to return to their normal positions by their own weight.

In operation the pistons with the buck thereon are permitted to assume their normal positions with the heads of the pistons resting upon the upper ends of the cylinders 80 which constitutes a rigid support for the buck.

The garment to be pressed is then spread out upon the buck in the usual manner and then the head is brought down either by 85 hand or, preferably, by means of the foot lever —17—, whereby the garment will be subjected to the maximum pressure capable of being produced by the foot lever, but if the lapels, pocket flaps, sleeve or trouser 90 cuffs are interposed between the pressing elements, considerably greater pressure would be required to properly shape those parts, and under those conditions the excess pressure may be readily supplied while the 95 press head is locked in its pressing position by the toggle —19— by simply opening the valve —52— to admit steam to both cylinders through their respective branches —51—, thereby forcing the buck with the 100 garment thereon upwardly against the under side of the press head with considerably greater force than could be produced by the pedal lever.

It is only necessary to open the valve 105 —52— for an instant, just sufficient to give the garment the extra pressure while still softened by the blast of steam previously admitted thereto, whereupon the valve may be returned to its normal position to open 110 the exhaust and allow the pistons to return.

Simultaneously with or immediately following this operation of the buck by the pistons, the valve —46— may be opened by depressing the pedal end of the lever —47— 115 to operate the section device —44— for withdrawing the steam from between the pressing elements so that the head may be instantly raised to release the garment with the assurance that the latter will be substantially dried and that no appreciable amount of moist vapor will be liberated in the room in which the machine is located.

In operating the pistons by steam, I am permitted to supply the cylinders with such 125 steam from the same source as that used for heating the pressing elements and moistening the garment, thereby reducing the operating parts of the machine to a minimum and permitting all of said parts to be in- 130

corporated in one and the same machine as a unitary article of manufacture, although it is evident that other fluid under pressure may be used as the operating means for said 5 pistons if desired without departing from the spirit of my invention.

What I claim is:

1. In a garment pressing machine, the combination of a buck and a press-head, 10 each movable independently of and toward and from the other, means for forcing the press-head toward the buck with a certain maximum pressure including a device for automatically locking the press-head under 15 said pressure, and separate means for forcing the buck toward the press-head with a greater pressure than that of the press-head while the latter is locked.
2. In a garment pressing machine, the 20 combination of a buck and a press-head, each movable independently of and toward and from the other, means normally supporting the buck in a certain plane for resisting pressure of the press-head, means for 25 forcing the press-head into pressing coaction

with the buck while the latter is in said plane, and separate means for advancing the buck slightly beyond its normal plane while the press-head is in its pressing position.

3. In a garment pressing machine, the combination of a buck and a press-head, each movable independently of and toward and from the other, means normally supporting the buck in a certain plane for resisting pressure of the press-head, means for 35 forcing the press-head into pressing coaction with the buck while the latter is in said plane, including a device for locking the press-head in its pressing position, and fluid-pressure operated means for forcing the buck slightly beyond said plane while the press-head is locked.

In witness whereof I have hereunto set my hand this 30th day of June, 1917.

JAMES B. SPENCER.
